EXCITATION CONTROL SYSTEM FOR
VAPOR ELECTRIC DEVICES

Joseph H. Cox, Forest Hills, Pa., assignor to Westinghouse Electric Corporation, East Pittsburgh, Pa., a corporation of Pennsylvania

Application May 27, 1943, Serial No. 488,637

2 Claims. (Cl. 315—127)

1

My invention relates to a vapor-electric device and particularly to an excitation control system for such devices.

In the operation of vapor-electric devices of the make-alive type, particularly when excited by means of saturating reactor circuits without compensation of voltage, when the voltage of the excitation supply falls to some value below normal, operation ceases because the energy of the firing impulse is too small to create a cathode spot. This value varies in various circuits so that if ignitron units are operated in parallel, as they are in large installations requiring large blocks of power, such as large electric chemical plants, in the event of a drop of a high line voltage, such as caused by a line fault, the various units cease operating in a ragged manner so that the last units to stop are overloaded and their breakers trip out because of their overload. When the line voltage is restored and excitation is resumed, the rectifiers remaining on the bus will be overloaded, and, consequently, their breakers will also trip out. This results in a station outage for a time sufficient to reclose all of the breakers and put the station back in operation. The result of such a prolonged outage is overspeeding of the generators and great accentuation of the system disturbance.

The earlier saturation excitation circuits sometimes stop igniting at a voltage of the order of 90% of normal voltage while some of the latter design circuits will maintain operation down to 80% of normal line voltage. I propose to eliminate the serious consequences of a drop in line voltage in conjunction with ignitron stations excited from the high line voltage by the use of a voltage relay responsive to the excitation voltage to simultaneously trip out the excitation voltage supply to all of the reactor firing circuits at some voltage above the failure point of the reactor system.

The simultaneous cutting out of all of the excitation systems permits immediate reclosing of the contactors of the excitation systems on restoration of line voltage and thus prevents the necessity of opening and closing the main breakers to restore the station to operation. The use of the voltage relay to control the excitation will, in general, limit the outage time to the length of time that the system fault actually exists, in general, too short a time to permit great overspeeding of the generators supplying the load.

It is, accordingly, an object of my invention to provide a control system for simultaneously de-energizing the excitation circuits of all the con-

2

verters of a parallel operating conversion system in response to a predetermined drop in excitation potential.

It is a further object of my invention to provide an excitation system for reducing the outage time caused by system disturbances.

Other objects and advantages of my invention will be apparent from the following description taken in conjunction with the accompanying drawing, in which:

Figure 1 is a schematic illustration of a vapor-electric conversion system embodying my invention; and

Fig. 2 is a schematic illustration of a single unit of the system showing the details of the unit connections.

In the illustrative embodiment of my invention, an alternating-current circuit 10 is connected to a direct-current circuit 11 by means of a plurality of vapor-electric devices A, B operating in parallel. For simplicity of illustration only two units are shown, but in normal installations a great many units are so connected. Each unit A, B of the device comprises a converter transformer 12 connected to the alternating-current circuit 10 by a circuit breaker 52 and to a direct-current circuit 11 by a circuit breaker 72, the flow of current between the circuits 10 and 11 being controlled by a plurality of vapor-electric valves 13 herein illustrated as of the make-alive type, in which each valve 13 comprises a main anode 14 and cathode 15 and has an excitation electrode 16 in contact with the cathode 15.

An impulsive circuit 20 is provided for periodically applying excitation impulses to the make-alive electrodes 16. The impulsive circuit 20 preferably is of the so-called reactor firing type in which a capacitor 21 is charged to a firing potential from any suitable source, herein illustrated as the high line 10, and the capacitor 21 is discharged by means of a non-linear reactor 22 preferably of the saturable reactor type.

For simplicity of illustration only two units of this system have been illustrated, but it will be understood that, in general, many units will be operated in parallel as certain operations such as that of electric chemical work frequently require power of the order of 200,000 kilowatts. In the event of a system fault producing a decrease in the high line voltage, the potential applied to the firing circuits 20 will likewise decrease, and at some point the firing circuits 20 will begin to fail to excite their associated converters.

To prevent this random occurrence I provide 55 circuit breakers 31 between the source of excita-

tion supply and each of the exciting circuits. These circuit breakers are simultaneously operated by means of a control relay 30 which is, in turn, controlled by means of a voltage responsive relay 29 connected to the potential of the source of excitation current. If desired, the breaker control relay 30 may be either manually or remotely controlled by means of a switch 28 in series with the winding of the relay.

In the operation of the system according to my invention, the breakers 52 and 72 will be closed after which the master relay 30 will be energized by closing the series switch 28, placing the system in operation. The operation then will continue as long as the high line voltage remains normal. However, should any disturbance cause a reduction in the high line voltage, the excitation potential will be decreased so that the voltage relay 29 will open its contacts, de-energizing the master control relay 30 which will simultaneously open the circuits to all of the impulsing circuits 20 so that all of the converters A, B comprising the system will be simultaneously shut down without opening either the breakers 52 or 72. As soon as the system disturbance has ceased, and the voltage has returned to normal, the voltage relay 29 will energize the master control relay 30 which simultaneously energizes all of the excitation circuits 20 and restores the station to normal operation with the minimum of actuation time.

While for purposes of illustration I have described the specific embodiment of my invention, it will be apparent that changes and modifications may be made therein without departing from the true spirit of my invention or the scope of the appended claims.

I claim as my invention:

1. An electric current translating system interconnecting two dissimilar electric circuits comprising a plurality of parallel operating converters, each of said converters including a plurality of vapor-electric valves of the make-alive type, a make-alive electrode for each of said

valves, a wave distorting network for each of said converters for periodically applying impulses to the make-alive electrode of the valves thereof, a source of control potential, circuit means connecting said source to each of said wave distorting networks, circuit breaker means in each of said circuit means, and a relay responsive to the potential of said source of control potential for controlling said circuit breaker means for simultaneously controlling each of said circuit means.

2. An electric current conversion system for transferring electric power between two dissimilar circuits, one of which is an alternating current circuit comprising a plurality of parallel operating valve type converters, a wave distorting network associated with each converter for supplying control impulses thereto, said wave distorting networks being unreliable when insufficient potential is applied thereto, a source of control potential, connections from said source to said wave distorting networks, a voltage responsive relay energized from said source, circuit breaker means for controlling the connections from said source to all of said wave distorting networks, and means energized by said voltage responsive relay for simultaneously actuating said circuit breaker means.
